UNITED STATES PATENT OFFICE.

FRANK SHAW, OF SYRACUSE, NEW YORK.

SHAFT-COUPING.

SPECIFICATION forming part of Letters Patent No. 674,479, dated May 21, 1901.

Application filed October 19, 1900. Serial No. 33,638. (No model.)

To all whom it may concern:

Be it known that I, FRANK SHAW, of Syracuse, in the county of Onondaga, in the State of New York, have invented a certain new and 5 useful Shaft-Coupling, of which the following is a specification.

My invention relates to improvements in shaft-couplings of the class set forth in my previous patent, No. 441,445, of November 25, 10 1890, and in my pending application, Serial No. 586,354, filed April 4, 1896, and has for its object the production of a device which is cheaply manufactured and is particularly effective and durable in use; and to this end it consists, essentially, in the combination, construction, and arrangement of the outer shell and the inner sleeve of the shaft-coupling, as hereinafter fully described, and pointed out in the claims.

In describing this invention reference is had to the accompanying drawings, forming part of this specification, in which like letters indicate corresponding parts in all the views.

Figure 1 is a longitudinal vertical sectional view of my improved shaft-coupling, its inner sleeve being shown in elevation and as operatively engaged with a shaft. Fig. 2 is an end view of a portion of my improved 30 shaft-coupling. Figs. 3 and 4 are transverse and longitudinal sectional views taken, respectively, on lines 33 and 44, Figs. 1 and 3, the shaft being omitted in Fig. 4. Fig. 5 is a plan view of the inner sleeve of my shaft-coupling, shown as split lengthwise and as 35 folded flat.

A A' and B B' are end and intermediate sections forming the outer shell of my improved shaft-coupling, and C is a shaft-receiving 40 sleeve arranged within said shell. The sections A A' and B B' are formed with conical tapering inner faces a and apertures a' and are drawn toward each other by clamping means, as bolts D. As best seen in Fig. 1, a number 45 of the apertures a' in the intermediate sections B B' are of greater size than the remaining apertures a' in said intermediate sections. Part of the bolts D are passed through the apertures a' of greater size in one of the 50 intermediate sections, and corresponding ends thereof are passed through the apertures a' in the adjacent end section and are engaged with said end section, and their opposite ends

are passed through the apertures a' of less size in the other intermediate section and are 55 engaged with said other intermediate section, and the remaining bolts D are passed through the apertures a' of greater size in said other intermediate section, and corresponding ends thereof are passed through the apertures in 60 the adjacent end section and are engaged with said end section, and their opposite ends are passed through the apertures of less size in the former intermediate section and are 65 engaged with said former intermediate section. By this construction and arrangement of the apertures a' and the bolts D it is possible, without liability of binding of the bolts, to use comparatively short bolts for effectively drawing the intermediate sections toward each other and drawing the end sections 70 toward the outer sides of the intermediate sections.

The inner sleeve C encircles the divisions of the shaft D' to be coupled, is preferably composed of spring metal, and is formed with conical or tapering ends which engage the inner faces a of the sections A A' and B B'. Said sleeve is also formed with longitudinal substantially equidistant slots c , extending from 80 one of its end faces into proximity to the opposite end face and with a plurality of additional substantially equidistant longitudinal slots c' , extending alternately between the slots c from said opposite end face into proximity to the former end face. The slots c divide the sleeve C into a number of yielding parts c^2 , which taper or decrease in thickness 85 toward the ends of the sleeve, are connected together at one end of the sleeve, and engage 90 the faces a of the sections A A' and B B' and the periphery of the shaft D', inserted within said sleeve C, and each slot c' extends from substantially the central point of the end edge of the connected end of one of the yielding parts c^2 and divides said yielding part into longitudinal yielding divisions or branches 95 connected together at the free end of said yielding part.

The described arrangement of the slots c c' 100 permits the parts c^2 and their divisions or branches to yield independently throughout almost their entire length and to positively and effectively engage and closely fit the divisions of the shaft D'.

The construction and operation of my shaft-

coupling will now be readily perceived upon reference to the foregoing description and the accompanying drawings.

Having thus fully described my invention, 5 what I claim as new, and desire to secure by Letters Patent, is—

1. In a shaft-coupling, the combination with an outer shell consisting of intermediate sections movable toward each other, and end sections 10 movable toward the outer sides of the intermediate sections, said sections having tapering inner faces; of clamping means for connecting one of the end sections to the intermediate section adjacent to the other end 15 section, clamping means for connecting said other end section to the other intermediate section, and a shaft-receiving sleeve arranged within the outer shell and provided with movable parts engaged with said inner faces and 20 with the periphery of the shaft inserted within the sleeve, substantially as and for the purpose described.

2. In a shaft-coupling, the combination with an outer shell consisting of end and intermediate sections having tapering inner faces, 25 bolts passed through one intermediate section and having corresponding ends engaged with the adjacent end section and their opposite ends engaged with the other intermediate section, and bolts passed through said other intermediate section and having corresponding ends engaged with the adjacent end section and their opposite ends engaged with the former intermediate section; of a shaft-receiving sleeve arranged within the outer shell and provided with movable parts engaged with said inner faces and with the periphery of the shaft inserted within the sleeve, substantially as and for the purpose specified.

3. In a shaft-coupling, the combination with an outer shell consisting of end and intermediate sections having tapering inner faces and apertures, a number of the apertures in the intermediate sections being of greater size 45 than the remaining apertures in said intermediate sections, bolts passed through the apertures of greater size in one intermediate section and having corresponding ends passed through the apertures in the adjacent end section 50 and engaged with said end section and their opposite ends passed through the apertures of less size in the other intermediate section and engaged with said other intermediate section, and bolts passed through the apertures of greater size in said other intermediate sections and having corresponding ends passed through the apertures in the adjacent end section and engaged with said end section and their opposite ends passed through 55 the apertures of less size in the former intermediate section and engaged with said former intermediate section, of a shaft-receiving sleeve arranged within the outer shell and provided with movable parts engaged with said inner faces and with the periphery of the shaft inserted within the sleeve, substantially as and for the purpose specified.

4. In a shaft-coupling, the combination with an outer shell consisting of end sections and separable intermediate sections between the former sections, said end and intermediate sections having tapering inner faces, and means for connecting one end section to the intermediate section adjacent to the other end section and for connecting said other end section to the other intermediate section; of a shaft-receiving sleeve arranged within the outer shell and having its opposite ends formed tapering and engaged with the inner faces of the sections, said sleeve being formed with longitudinal substantially equidistant slots extending from one end face into proximity to the opposite end face, and thereby forming a plurality of yielding parts connected together at one end of the sleeve, and being also formed with additional slots extending alternately between the former slots from said opposite end face of the sleeve into proximity to the former end face thereof for dividing said yielding parts into yielding divisions or 80 branches, the divisions or branches of each yielding part being connected together at the free end of said part, substantially as and for the purpose set forth.

5. In a shaft-coupling, the combination with an outer shell consisting of end and intermediate sections having tapering inner faces, bolts 95 passed through one intermediate section and having corresponding ends engaged with the adjacent end section and their opposite ends engaged with the other intermediate section, and bolts passed through said other intermediate section and having corresponding ends engaged with the adjacent end section and their opposite ends engaged with the former 100 intermediate section; of a shaft-receiving sleeve arranged within the outer shell and having its opposite ends formed tapering and engaged with the inner faces of the sections, said sleeve being formed with longitudinal 105 substantially equidistant slots extending from one end face into proximity to the opposite end face, and thereby forming a plurality of yielding parts connected together at one end of the sleeve, and being also formed 110 with additional slots extending alternately between the former slots from said opposite end face of the sleeve into proximity to the former end face thereof for dividing said yielding parts into yielding divisions or 115 branches, the divisions or branches of each yielding part being connected together at the free end of said part, substantially as and for the purpose set forth.

In testimony whereof I have hereunto 125 signed my name, in the presence of two attesting witnesses, at Syracuse, in the county of Onondaga, in the State of New York, this 5th day of January, 1900.

FRANK SHAW.
